UNITED STATES PATENT OFFICE.

JOHN EDWARD THORNTON, OF WEST HAMPSTEAD, LONDON, ENGLAND.

MULTICOLOR CINEMATOGRAPH AND OTHER FILMS.

Original application filed May 5, 1924, Serial No. 711,254, and in Great Britain May 18, 1923. Divided and this application filed November 3, 1925. Serial No. 66,603.

This invention relates to the manufacture and production of multi-color film-material of the screen-filter type but of special construction, for the production of cinematograph or other varieties of color-pictures of either negative or positive form; and its chief characteristic consists in its having two screen-filters arranged side-by-side upon a film of double-width or double-area, and with 10 double-area of sensitive surface, for each complete color-picture record made on the sensitive film.

The purpose of the two filter-screens for each color-picture is to enable the picture to 15 be formed or constructed in two parts, as two half-pictures, one upon each half of the film area; each section or half-picture containing only two of the colors and each being different in coloring from the other, the complete set of colors being represented on the one double-film by the two half-pictures.

The group of colors forming each picture may be four, all of which are different; or the group may comprise only three colors, 25 with one of the colors duplicated to appear in each half-picture in order to make up the group of four; in either case the colors form a complementary set or group.

This improved film-material is designed 30 for the production of color pictures made as described in my application, Serial No. 711,254, filed May 5, 1924, of which this application is a division, and in my applications, Serial Nos. 66,602 and 66,604, both filed November 3, 1925.

The invention will be described with reference to the accompanying drawings, in which:

Figure 1 is a plan view of a double width film material.

Figure 2 is a plan view, greatly enlarged, of a portion of the color screens adjacent to the center line and showing the two halves formed with alternating lines in two different colors to give a four-color analysis.

Figure 3 is a similar view in which one color is duplicated upon each half to give a three-color analysis.

Figures 4, 5 and 6 are similar views of different patterns of color screens.

Figure 7 is a section taken on line 7—7 of Figure 5 illustrating a positive film material of half standard thickness and double width having screen filters coated with panchromatic emulsion.

Figure 8 is a similar section of a negative film material showing the material of double width and standard thickness.

Figure 9 is also a similar section of a positive material of half standard thickness and double width to which a temporary reinforcing layer of paper has been applied.

For cinematograph pictures the film-material is manufactured as continuous lengths either in narrow strips or preferably as wide webs to be afterwards cut into narrow strips; and one variety is manufactured with a transparent base or support of standard thickness for the production of negative pictures and another variety is made with a base of only half standard thickness for the production of positive pictures; otherwise the characteristics of both varieties are identical.

I will now describe the construction and manufacturing methods as applied to the production of continuous strips of film for cinematograph pictures, in which the two screens are placed side-by-side upon a double-width strip, (Fig. 1) which may have been formed of that width or as a wide web from which it has been cut after completion of all the manufacturing processes.

The same description will apply substantially to the manufacture of non-cinematograph material with the difference only of size or area of the base and its nature and thickness.

Manufacture of the sensitive negative film-material.

The negative-film-material (Fig. 8) comprises four separate and different layers which are all so indissolubly united that they form one homogeneous strip. The layers are formed in the order and of the composition as follows:—

(1) A base or support of transparent waterproof material such as celluloid, cellulose-acetate, or the like, with a thickness of about .00450 inch.

(2) A substratum of permanently adhesive material with a thickness of about .00005 inch.

(3) A screen-layer of suitable colloid material with a thickness of about .00040 inch in or upon which are formed two screen-filters side-by-side.

(4) An image layer of gelatino-silver-bromide panchromatic emulsion with a thickness of about .00100 inch.

The above arrangement of layers produces a sensitive negative-film-material with a total thickness of about .00600 inch, but it will be understood that these figures are approximate, being given as an illustration and not as a limitation.

For the negative-film-material the sensitive emulsion used is preferably of the highest speed capable of yielding good results.

10. *Manufacture of the sensitive positive film-material.*

This thin positive-film-material (Fig. 7) comprises four separate and different layers which are all so indissolubly united that they form one homogeneous strip. These different layers are formed in the order and of the composition as follows:—

(1) A base or support of transparent waterproof material such as celluloid, cellulose-acetate, or the like, with a thickness of about .00150 inch.

(2) A substratum of permanently adhesive material with a thickness of about .00005 inch.

(3) A screen-layer of suitable colloid material with a thickness of about .00040 inch in or upon which are formed two screen-filters side-by-side.

(4) An image layer of gelatino-silver-bromide panchromatic emulsion with a thickness of about .00100 inch.

The above arrangement of layers produces a sensitive positive-film-material with a total thickness of about .00300 inch, but it will be understood that these figures are approximate, being given as an illustration and not as a limitation.

For positive-film-material the sensitive emulsion used is preferably of much slower speed than used for negatives and of very fine grain.

45. *Manufacture of reinforced positive-film-material.*

The thin positive-film-material (Fig. 9) above described requires to be printed, developed, or otherwise treated with great care, owing to the fact that it is only half the standard thickness and therefore liable to damage during the rough handling often given in the film printery.

This objection can however be overcome by constructing the positive film-material with the addition of a self-contained but temporary reinforcing-strip of porous paper, upon which it is built or to which it is separately attached during the process of manufacturing the film-material itself. This reinforcing strip is removed and thrown away when the two section-films have been developed, or at any other convenient stage of the process of producing the color-positive.

Each section of such positive film-material 65 will therefore comprise six layers, instead of

four as in the first example, arranged in the following order:—

(1) A base or support of transparent waterproof material such as celluloid or the like, with a thickness of about .00150 inch.

(2) A substratum of permanently adhesive material with a thickness of about .00005 inch.

(3) A screen-layer of suitable colloid material with a thickness of about .00040 inch in or upon which are formed the two-color filter-screens.

(4) An image layer of gelatino-silver-bromide panchromatic emulsion with a thickness of about .00100 inch and slightly hardened during manufacture.

(5) A porous colloid layer, such as very soft easily soluble gelatine, glue, or the like, free from alum or other hardening agent, with a thickness of about .00050 inch, attached to layer 6.

(6) A temporary reinforcing strip of porous paper of about .00250 inch thick, attached to layer 5.

In manufacturing this reinforced film-material the process of manufacture is divided, so that the two separate parts A and B of the complete material are first separately formed and afterwards combined and amalgamated to produce only one strip at a later stage of the manufacture.

The first part A of this strip therefore comprises only layers 1, 2, 3 and 4.

The second part B comprises only layers 5 and 6.

The two parts A and B are separately manufactured and preferably before drying each is coated with a very thin adhesive substratum of porous, soluble, glue, the one coating upon face 4 and the other coating upon face 5. Each of these soluble adhesive substratum-layers need only be about .00005 inch thick. Alternatively they may be applied when each film-part is dry. But in either method of application the two film-parts A and B are dried after application of the two soluble adhesive substrata.

The two soluble adhesive substrata of the two film-parts A and B are next slightly moistened, then brought into face-contact by rolling pressure, applied until the two substrata have produced a perfect and indissoluble union of the two faces 4 and 5 of the film-parts A and B, so that a compound film is produced comprising the parts A and B with their layers 1 to 6.

The porous layer 5 performs a double function. Firstly, it serves as an adhesive which adheres tenaciously to the grain or protuberances of the paper surface, and secondly as a filler by which the depressions formed by the grain can be filled up level and a perfectly smooth top surface obtained on the paper. If necessary a second application may be made. Therefore, owing to the smooth sur-

face of this layer no paper-grain is reproduced upon the picture when the printed image is developed.

The relative degrees of slight hardness of the layers 2, 3, 4 are so adjusted during manufacture that they will not dissolve when a suitable liquid is applied to dissolve the soluble adhesive substratums when it is desired to remove the paper layer 6 and its adhering porous layer 5 after the film is developed.

The above process produces a film material with a total thickness of about .00500 inch, which can be handled with safety during the various processes in the film printery, but may be increased by use of a thicker paper layer 6.

Panchromatizing the film-material.

In each of the foregoing varieties of sensitive film-material the panchromatic dyes may be applied to the film in the emulsion itself, or preferably by soaking in baths after drying the coated emulsion; or they may even be applied through the outer paper reinforcing strip.

Screen-filters for four-color pictures.

The filter-screen for four-color consists of an immense number of exceedingly fine colored dots, lines or mosaic pattern, (Figs. 2, 4 and 5) a fuller description of which is given hereinafter. These are arranged in two groups, side-by-side upon the two halves of the double-width film strip. One section consists of dots, lines or other pattern of two colors equally intermixed, and the other section of two other colors equally intermixed. The colors used for a four-color screen-filter (Figs. 2, 4 and 5) set are preferably crimson-red and blue-green for one half of the double-width negative film, and blue-violet and orange-yellow for the other half. These form one filter set containing the complementary colors of red and green, and another filter-set containing the complementary colors of blue and yellow. Each half of the double-width film therefore contains its own complementary color, and the two halves are also complementary to each other. This particular arrangement however is not necessarily a hard and fast rule, though it is preferred, but if desired the complementary colors of each pair may be arranged upon the adjoining half instead of upon the same half width.

Screen-filters for three-color pictures.

The filter-screen for three-color is of a similar character consisting of fine dots, lines, or mosaic pattern, but the colors comprise only crimson-red, blue-green, and blue-violet (Figs. 3 and 6) and are therefore only semi-complementary. They are arranged in two groups, one upon each half of the double-width film as in the preceding example, but

one of the colors is repeated upon each half. For example one half-width may have a filter-screen of red and green, and the other a filter-screen of blue-violet and green. Or any other preferred arrangements of the combination may be used; for instance by duplicating the red filters on the negative the complementary color, green, will predominate in the positive because it will be repeated upon both halves.

Manufacturing the filter-screens for both negative and positive films.

The formation of the color-screens upon the film base may be carried out by a number of known processes, but I prefer to use one of the following methods according to whether the accidental irregular dot-grain is required, (Figs. 5 and 6) or a regular line-screen pattern (Fig. 4) is preferred. The screen is similar for both negative and positive kinds of film.

Of the great number of screen-forming processes hitherto designed by investigators most are very expensive to produce, if three, four, or greater number of colors are required, and usually it is exceedingly difficult to secure uniformity throughout continuous lengths of cinematograph film by any method heretofore used.

The methods of manufacture hereinafter described are very simple, the results reliable, and they permit of readily manufacturing unlimited lengths of screen film at low cost.

These difficulties are tremendously reduced in this film by reason of the fact that each of its sections contains only two colors, which are much easier to make than three or four, the four colors being obtained by the combined use of two such sections. The expense and trouble accruing from differential blocking out and differential dyeing (as in old-style filter-screens) is tremendously reduced, the labour required being less than half.

For four-color one half the double-width film will therefore possess a screen-pair of two complementary colors, and the other half a similar screen-pair, but of different complementary colors, thus forming a quadrat (Figs. 2, 4 and 5).

For three-color one of the colors is repeated upon both halves, as hereinbefore described in detail, thus forming a triad (Figs. 3 and 6).

The color-screens of both the negative and positive films are manufactured by the same methods.

Irregular-dot filter-screens produced non-photographically.

The double-width celluloid or similar film-base (Fig. 1) is coated with the substratum-layer 2 and next with the screen-layer 3 (Figs. 7, 8 and 9). Before the latter is dry and hard

- a quantity of minute colored grains of starch, gelatine, resin, or other material is applied to the surface by scattering the grains from an elevated position. The coloring dyes are insoluble, so that each grain is non-absorbent to other dyes. The film is then subject to rolling pressure until the grains are driven into the soft colloid coating until flush with its surface. The film is next dried.
- 10 The next operation is to apply to the soft gelatine a dye of complementary color which will be absorbed by the gelatine only in the spaces between the insoluble dye grains. The film is next dried, and the panchromatic emulsion superimposed thereon in any known manner.

Regular line or mosaic filter-screens produced photographically.

- 20 To produce regular-pattern screens I prefer photograph printing methods, of which two forms stand above all others for simplicity of manufacture.

In the first of these methods the celluloid base is first coated with its substratum-layer 2 and then with its screen-layer 3 (Figs. 7, 8 and 9). This layer consists of gelatine, albumen or other suitable colloid containing a suitable mordanted dye. After drying it is sensitized in a bichromate bath, or a suitable bichromate may be mixed with a suitable dye and with the colloid, the mixture being next applied to the film in a layer of even thickness and correct depth. The dyes used are of different colors for each screen upon each half-width.

The film (Fig. 4) is next printed under a line-screen of very fine range, say from 500 to 1000 to the inch, printing being preferably effected by exposure to mercury-lamp tubes.

The film is next well washed until all dye is removed from the soft non-printed colloid, leaving behind the insoluble colloid in which the remaining dye is imprisoned.

The film is next dried and is next subjected to a further dye bath that will color only the soft gelatine and leave the insoluble dyed portions untouched.

50 The dye last applied is next subjected to a mordanting bath to fix the color unless self-mordanting dyes have been used.

The panchromatic sensitive emulsion is next applied in the usual way.

55 In the second method silver-sensitized film is used upon which to print the screen, and has the advantage of quicker printing. After development the line-printed film (Fig. 4) is treated in a bath which renders the lines insoluble in proportion to the deposit of metallic silver, thus producing a condition of insoluble colloid and enclosed dye similar to the bichromate example. The second dyeing is already described.

Irregular-dot filter-screens produced photographically. 65

By using a negative printing cliché covered with fine irregular dots of opaque substance suitably scattered, and printing by either the first or second (photographic) method; or by making such a negative by reduction from a master cliché having larger grains, a negative with very fine dots (Figs. 5 and 6) is secured; photographically printed color screens can thus be made with the irregular dot formation. 70

75 With the photographic methods described all differential printing and blocking-out are abolished, the process for a four-color result being reduced to one exposure and one dyeing for each half the double-width film, the two screen-halves being produced side-by-side simultaneously.

80 What I claim as my invention and desire to protect by Letters Patent is:—

1. A strip of film material for the production of color pictures comprising a transparent support having two filter-screens arranged side-by-side, one screen having two colors and the other screen having two other colors, and a layer of panchromatic emulsion covering said screens. 90

95 2. A strip of film material for the production of color pictures comprising a transparent support having two color filter-screens arranged side-by-side on the same face thereof, each screen containing two colors, and a layer of panchromatic emulsion applied to and covering said screens.

100 3. A strip of film material for the production of color pictures comprising a transparent support of double picture area having two color filter-screens arranged on its respective picture-areas, each screen containing two colors, the colors of one screen being different from those of the other screen, and a layer of panchromatic emulsion covering said screens. 105

110 4. A strip of film material for the production of color pictures comprising a transparent support of double picture-area in width and having two color filter-screens arranged on the same face and on the respective areas thereof, each screen containing two colors, the colors of one screen being different from those of the other screen and a layer of panchromatic emulsion covering said screens. 115

120 5. A continuous strip of cinematograph film material for the production of color pictures, comprising a strip of transparent celluloid having two screen-filters formed side-by-side thereon, one screen comprising two complementary colors and one screen two other colors, and a layer of panchromatic emulsion covering said screens. 125

125 6. A continuous strip of cinematograph perforated film material for the production

of color pictures of the screen-filter class in series, comprising a double-width strip of transparent waterproof material, a layer of adhesive sub-stratum superimposed upon and amalgamated with said strip, two screen-filters formed side-by-side, one upon each half-width of the strip and united with the substratum thereon, each screen consisting of two complementary colors, said screens forming a complementary set of color-analyzers, and a layer of rapid panchromatic emulsion superimposed upon and united to the screen-filters, the whole forming a complete color film material capable of recording two colors upon each of the half-widths thereof.

7. A continuous strip of cinematograph perforated film material for the production of color pictures of the screen-filter class in series comprising a double-width strip of celluloid, a layer of adhesive substratum superimposed upon and united with said celluloid strip, two screen-filters formed side-by-side on said strip and united with said substratum, one screen occupying each half-width of the strip and each screen consisting of two complementary colors, said screens forming a set of color-analyzers, and a layer of panchromatic emulsion united to the screen-filters.

8. A strip of film material of the class described comprising a transparent flexible support having color filter-screens on a face thereof, a layer of sensitive emulsion covering said screens, and a flexible reinforcing strip removably applied to the layer of sensitive emulsion.

9. A strip of film material of the class described comprising a transparent flexible support having color filter-screens on a face thereof, a layer of sensitive emulsion covering said screens, a flexible reinforcing strip, and an easily soluble medium uniting said reinforcing strip with said layer of emulsion.

10. A strip of film material of the class described comprising a transparent flexible support having color filter-screens united to a face thereof, a layer of sensitive emulsion covering said screens, said emulsion being exposable through the support and the filter-screens, and a reinforcing strip attached to the layer of emulsion and removable therefrom after exposure of the emulsion.

11. A temporarily reinforced continuous strip of film material for the production of color pictures of the screen-filter class in series, comprising a double-width strip of transparent waterproof material, a layer of adhesive substratum superimposed upon and amalgamated with said strip, two screen-filters formed side-by-side upon the strip and united to said substratum thereon, one screen-filter occupying each half-width of the strip and each screen consisting of two complementary colors, said screens forming a set of color-analyzers, a relatively hardened layer of panchromatic emulsion covering and united to the screen filters, a relatively soft porous colloid layer attached to said layer of emulsion, and a reinforcing strip of porous paper attached to the soft colloid layer.

In testimony whereof I have hereunto set my hand.

JOHN EDWARD THORNTON.
